Frank C. Myhr.

UNITED STATES PATENT OFFICE.

WILLIAM S. HUNKINS, OF LOS ANGELES, CALIFORNIA.

FASTENING DEVICE.

1,354,485.

Specification of Letters Patent.

Patented Oct. 5, 1920.

Application filed June 8, 1920. Serial No. 387,376.

To all whom it may concern:

Be it known that I, WILLIAM S. HUNKINS, a citizen of the United States of America, residing at Los Angeles, California, have invented a new and useful Fastening Device, of which the following is a specification.

My invention relates particularly to means for detachably connecting a garter to a corset.

The invention in its preferred form contemplates the use of a bushing, a sleeve and a two-part frame for detachably connecting the bushing and sleeve. The bushing is preferably housed in a tape or tab carried by the corset or waist, and the sleeve is carried by another piece of tape or garter. Special details of construction will be understood from the following specification.

Figure 1 is a front view of construction embodying improvements of my invention;

Fig. 2 shows the parts detached;

Fig. 3 is a view showing the preferred method of mounting the bushing;

Fig. 4 is a vertical section on the plane of the line 4—4 of Fig. 3;

Fig. 5 is a plan view of the bushing of Figs. 3 and 4;

Fig. 6 is a front view of the sleeve and two-part frame, showing the parts in full lines in the position of Fig. 2, and showing in dot and dash lines the position of the movable part of the frame corresponding to the position of Fig. 1;

Fig. 7 is a view of the parts of Fig. 6 taken from the left;

Fig. 8 is a section on the plane of the line 8—8 of Fig. 6;

Fig. 9 is a view of the parts of Fig. 6, taken from below with the frame in its closed position;

Fig. 10 is a detail of the blank from which the sleeve is formed;

Figs. 11 and 12 are perspective views of modified forms of bushings; and

Fig. 13 is a perspective view of a modified form of frame.

14 and 15 are the two tape members which it is desired to detachably connect. The upper part may be secured to a corset, waist or other member, and the lower part may be a part of the garter. Preferably the part 14 is of non-elastic material, such as webbing or tape, and the part 15 is preferably elastic. The bushing 16 is suitably secured to the tape or tab 14 and preferably housed

entirely within it. The sleeve 17 is preferably housed entirely within the upper end of the tape 15. The sleeve and bushing are connected by two U-shaped members 18 60 and 19.

In the form shown in Figs. 3, 4 and 5, the bushing 16 is provided with two ears or tangs 20, 20, with tapered slots 21 between these ears and the ends of the bushing, which slots are adapted to receive the edges 14' of a folded strip which forms the tape 14. Preferably the ends of the ears 20, 20 are offset, as shown in Fig. 5, to facilitate assembly of the bushing and 70 ears with the edges of the tape strip. When the ends of the tape 14 are brought together they may be secured directly to the corset or other support, so that no special stitching or fastening of the bushing to the tape 75 is necessary. In Fig. 11 the bushing 16' is provided with sharp tangs 20' for preventing it from shifting longitudinally in the tape. In Fig. 12 the bushing 16'' is provided with tangs 20'' adapted to engage 80 the edges of the tape and prevent endwise movement of the bushing. It will be understood that a tape such as shown in Figs. 3 and 4 or an ordinary woven tape may be employed with the bushings of Figs. 85 11 and 12.

One end of the frame member 18 is preferably permanently secured in one end of the sleeve 17 in any suitable manner. The part 19 has one arm slidably engaged in 90 the parts 22 and 23 of the sleeve. The end 24 is preferably bent at an angle, so as to co-act with the spring jaws 25 of the sleeve when the parts are in the position shown in Figs. 1 and 9. The mouth 26 of the jaws 95 25 is preferably somewhat expanded, so as to yieldingly engage the end 24, and not only prevent it from moving longitudinally but also prevent it from rotating when the parts of the frame are closed. A part 100 of the sleeve is cut away, as at 27, to permit the member 19 and its end 24 to be slightly rotated or tilted, as shown by dotted lines in Fig. 8, to facilitate connection and disconnection with the bushing 16. 105

By this construction it will be understood that the bushing 16 is completely housed and concealed by the tape 14 and securely held in position, and at a minimum cost. It will also be understood that with this detachable connecting device it is possible to manufacture a corset or waist with attached 110

non-elastic tabs and bushings and carry these in stock for any length of time, and then, when it is desired, fresh elastic garters may be readily attached. It will also be possible, at any time, to detach the elastic part of the garter when it is desired to launder the garment, or in case it is desired to replace the old garter with a new one.

The construction is simple, consists of but few parts, and is compact and unobtrusive.

Although the device is secure when the parts are in the position of Fig. 1, the parts may be readily disconnected by drawing out the member 19 into the position shown in Figs. 2 and 6, whereupon the end of the member 19 may be tilted into the dotted position of Fig. 8, and the member 18 will then be withdrawn from its end of the bushing 16 into the position of Fig. 2.

It will be understood that various changes in construction and arrangement may be made without departing from the spirit and scope of my invention as set forth in the following claims.

25 In the form shown in Fig. 13, the part 18' is provided with a projection 18'', to prevent it from turning in the sleeve 17', and the part 19' operates as in the other form.

I claim:

30 1. The combination of a non-elastic corset tab, a bushing housed therein, an elastic garter tape, and a fastening device carried thereby and having a member detachably connected in said bushing.

35 2. The combination of a tab, a bushing secured thereto, a tape, and a fastening device carried thereby and having two U-shaped members engaging in said bushing.

3. The combination of a tape, a bushing

carried thereby, a second tape, a sleeve carried thereby, and a two-part frame detachably connecting said bushing and said sleeve. 40

4. The combination of a bushing, a tape, a sleeve carried thereby, a U-shaped member having one arm secured to said sleeve 45 and the other arm slidably engaged in said bushing, and a second U-shaped member having its arms respectively slidable in said sleeve and in said bushing.

5. An attachment device comprising a 50 bushing having longitudinally extending ears, and a folded tape embracing said bushing and having its edges folded about said ears.

6. An attachment device comprising a 55 sleeve, two U-shaped members secured thereto, one of said members having a sliding engagement with said sleeve, and a snap catch for holding it in place.

7. An attachment device comprising a 60 combination of two folded tapes, a tubular bushing concealed in one of said tapes, and a wire fastening mounted in the other tape, and having two ends detachably housed in said bushing. 65

8. An attachment device comprising two tapes, a tubular bushing carried by one tape, and a fastening device carried by the other tape, and having two wire ends bent toward each other and housed in said bushing. 70

9. As an article of manufacture, a tubular bushing open on opposite ends and having an anchorage portion with ears extending longitudinally of the bushing and leaving slots between the ears and the ends of the 75 bushing.

WILLIAM S. HUNKINS.
